WALL ANCHORING DEVICE

Claude J. Herschel, St. Louis, Mo.

Application November 10, 1941, Serial No. 418,565

3 Claims. (Cl. 72—115)

The present invention relates to new and useful improvements in anchoring devices and has particular reference to a device for anchoring the studding of partitions and similar wall structures.

An object of the invention is the provision of an anchoring device which may be quickly and easily mounted in anchoring position.

Another object of the invention is to provide an anchoring device having bendable parts which may be readily disposed to grip a stud or the like.

A further object of the invention is the provision of an anchoring device which may be arranged in varying positions in accordance with the nature and condition of the wall structure.

Still another object of the invention is to provide an anchoring device of the aforesaid character which is relatively simple and durable in construction and which is highly efficient in use.

Other objects and advantages will be apparent from the following description and appended claims.

In describing my invention in detail, reference will be had to the accompanying drawing illustrating a practical adaptation of the invention, and in which

Figure 1 is a perspective view of the improved anchoring device in fully open position.

Figure 2 is a similar view showing the device with parts thereof bent to engage a wall stud in one arrangement.

Figure 3 is a top plan view of the same showing the device in stud engaging assembly.

Figure 4 is a side elevational view of the same.

Figure 5 is a perspective view of the device in another stud engaging arrangement.

Figure 6 is a top plan view of the same in association with a wall stud, and

Figure 7 is a side elevational view of the same.

With reference to the drawing, wherein like characters of reference denote corresponding parts throughout the several views, 10 generally designates an anchoring device constructed in accordance with the invention and which may advantageously be formed of sheet metal. In its fully open position, after shaping and prior to its arrangement for stud anchoring, the device is in the form of an elongated mainly flat plate having a center plate section 11 of angular L-shaped configuration in plan. From one straight edge of the body section 11 extend a pair of complementary elongated end sections 12 and 13 of angular cross section. Each of these end sections embodies a flange 14 having its inner end bent upwardly at the edge of the center section 50 55

and extending parallel with said center section in a plane offset and above the center. The inner edges of these flanges are spaced apart to provide a narrow slot 15 therebetween. The outer sides of the end sections 12 and 13 are formed with longitudinally extending right angular flanges 16, projecting upwardly when the device is in a normal horizontal position. The inner ends of these flanges 16 are formed with a diminishing taper and merge into the corners of the center section. Thus, in cross section the pair of end sections 12 and 13 form a channel shaped contour having a width slightly less than the length of the edge of the center section 11 with which they are connected.

At the opposite side edge of the section 11 are provided similar end sections embodying elongated angle members having their inner ends connected integrally with the section 11, with the section 18 merging into the projecting edge of the center plate opposite the end section 13 and the complementary end section 17 merging into the setback or recessed edge of the center section opposite the end section 12, as clearly shown at Figure 1. The horizontal flanges of the end sections are provided with longitudinally elongated fastener receiving apertures 19.

The device 10 is particularly useful for anchoring a support member, as for example the channel shaped studs S of a lath reinforced plaster partition wall W. The device is constructed to permit of its mounting transversely of the wall as shown at Figure 3 or longitudinally thereof as illustrated at Figure 6 in accordance with the particular nature and structural condition of the building in which the wall is to be erected.

In its transverse arrangement the end projecting sections 12 and 17 are fastened to the flooring by nails or suitable fastening means, as shown to advantage at Figure 3 while the directly opposed end sections 13 and 18 are bent to right angular vertical or upwardly directed positions to embrace opposite corner portions of the stud. These embracing end sections of the anchor are firmly tied to the stud by the usual binding wire B.

Where the building structure is such that it is advantageous to dispose the anchor longitudinally of the partition wall W the projecting end sections 12 and 18 are fastened horizontally to the concrete or other flooring while the diagonally opposed end projections 13 and 17 are bent upwardly on their bending edges joining the center section to provide upstanding portions embracing diagonally opposed parts of the stud, as

best shown at Figure 6. These stud embracing sections are securely tied to the support member as illustrated at Figure 7.

Thus, the improved anchoring device affords a relatively simple and inexpensive structure for anchoring wall studding and similar support members with reference to floors or ceilings, providing a device which may be quickly and easily mounted in anchoring position at varying angular positions with reference to the wall and studs and which will firmly embrace the studs to hold the same in position.

It is to be understood that the invention is not confined to the specific construction, arrangement or use illustrated and described and that considerable modification may be made therein within the spirit of the invention as defined by the appended claims.

I claim:

1. A wall anchoring device comprising a flat center section, a plurality of elongated end sections extending from opposed edges of the center section, the said end sections being of angular cross section and bendable at their juncture with the center section in directly or obliquely opposed

10 pairs to positions perpendicular to the center section for embracing a wall support member.

2. In an anchoring device, a flat center section of angular configuration, a pair of elongated end sections extending from one straight edge of the center section, a pair of elongated end sections projecting in a direction opposed to the first mentioned end sections from the angularly offset edges of the center section, the said end sections being disposed in parallel spaced apart pairs and having apertures therein for engaging plaster elements and right angular flanges formed at the outer edges of the said end sections.

3. In a device of the character described, a center section, and a plurality of end sections having bendable connection with opposed edges of the center section, the said end sections being disposed for bending from positions proximately co-planar with the center section to positions perpendicular thereto, the end sections at one side of the center section having their bendable connections disposed in transversely offset positions whereby the end sections may be arranged to embrace members of varying cross sectional contour.
